[57] **CLAIM**

The ornamental design for an adjustable medical tubing support frame or similar article, as shown and described.

DESCRIPTION

FIG. 1 is a perspective view of the adjustable medical tubing support frame or similar article;

FIG. 2 is a front elevational view thereof, the broken lines illustrating one of its various adjusted configurations;

FIG. 3 is a side elevational view thereof; and

FIG. 4 is a top plan view thereof.

FIG. 1.

FIG. 2.

FIG. 3.

FIG. 4.
